UNITED STATES PATENT OFFICE

THOMAS WILLIAM BYRNE, OF DORCHESTER, MASSACHUSETTS

GOLF BAG

Application filed January 9, 1928. Serial No. 245,281.

This invention relates to a golf bag.

One object of the invention is to provide a golf bag which may be placed upon the putting green without injury thereto.

5 A further object of the invention is to provide a golf bag having a novel and accessible pocket for holding golf balls and other articles.

10 A further object of the invention is to provide a golf bag with a novel handle for carrying the bag which permits accurate balancing in the hand without adjustment of the handle.

In the drawings illustrating the preferred 15 embodiment of the invention, Figure 1 is a perspective of the golf bag; and Fig. 2 is a longitudinal section of the same.

One feature of the present invention contemplates the provision of a golf bag in 20 which provision is made for holding the club heads from the ground when the bag is laid flat upon the ground. The present practice and in fact the rules of the game require a player to lay his golf bag off of the green so 25 as to prevent injury to the green. This not only consumes time adding to the congestion of the course, but in many instances the rule is disregarded and injury to the green results from the club heads digging into the putting 30 surface.

Another feature of the invention resides in the provision of an accessible pocket contained within the bag and at the mouth portion thereof.

35 A further feature of the invention resides in the provision of a handle for the bag which is sufficiently elongated so as to permit the position of the hand to be adjusted in the handle within sufficient limits to properly 40 balance the bag in accordance with the different number of clubs used by individual players. In this manner a standard construction of handle may be used by players carrying varying numbers of clubs.

45 Referring to the drawings, in which a golf bag embodying the different features of the invention has been illustrated, 10 represents the body of the bag which may be of any usual or preferred construction. 12 represents 50 the mouth of the bag and which is

formed to provide a flat under surface 14 for affording a substantially flat bearing upon the ground. The body of the bag being usually made flexible, conforms to this flat surface 14 to present a flat elongated bearing upon which the bag may be rested upon the putting green without doing any damage. The mouth of the bag is preferably formed by a steel frame 16, the under side of which is made flat.

55 In order to hold up the heads of the clubs, herein shown as 20, from the ground, the bag is sub-divided by a cross member 22 preferably located at the mouth of the bag. As herein shown the cross member 22 comprises a steel bar secured to the frame 16, and in order to prevent the clubs being inserted into the bag through the opening below the cross member 22 a pocket 25 is formed in the mouth of the bag below the cross member 22. 60 Preferably the pocket 25 is of tapered section as shown, so that it will not interfere with the introduction of the club handles into the bag. The mouth of the pocket is 65 preferably made at the mouth of the bag 70 itself to provide accessibility into the pocket and the mouth of the pocket may be closed by a cover member 30 hinged and fastened by a conventional form of fastener. This 75 pocket may be used for golf balls and different sorts of golfing and wearing articles, including ladies' toilet articles.

80 The illustrated golf bag is preferably provided with an elongated handle of a length much longer than the width of the hand in order to permit the hand to be shifted into different positions indicated in full and dotted lines in Fig. 2 to correctly balance the bag when the latter is being carried. Heretofore attempts have been made to provide 85 elaborately constructed adjustable handles but their adjustment has been inconvenient and troublesome. This present handle enables the player to correctly balance the bag by shifting his hand in the handle irrespective of the particular number of clubs in the bag.

90 While the preferred embodiment of the invention has been illustrated and described, it will be understood that the invention may be 95

embodied in other forms within the scope of the following claim.

Having thus described the invention what is claimed is:—

- 5 A golf bag including a body permanently closed at one end and having an open mouth portion flat on one side and arched on the other, and a pocket within the body at the mouth thereof and having one side against
- 10 the flat side of the body and its opposite side extending across the mouth in spaced relation to the flat side of said mouth, the last mentioned side of the body being inclined inwardly of the body from the mouth towards
- 15 the flat side, said pocket opening in the same direction as the mouth.

In testimony whereof I have signed my name to this specification.

THOMAS WILLIAM BYRNE.
